UNITED STATES PATENT OFFICE.

MIKE WOLAK, OF ROCHESTER, NEW YORK.

DESIGN FOR A PHONOGRAPH.

57,409.

Specification for Design.

Patented Mar. 15, 1921.

Application filed October 6, 1920. Serial No. 415,167. Term of patent 7 years.

To all whom it may concern:

Be it known that I, MIKE WOLAK, a citizen of Ukraine, residing at Rochester, in the county of Monroe and State of New York, have invented a new, original, and ornamental Design for a Phonograph, of which the following is a specification, reference being had to the accompanying drawing, forming part thereof.

The figure is a view in perspective of a phonograph, showing my new design.

I claim:

The ornamental design for a phonograph as shown.

MIKE WOLAK.
